(57) **CLAIM**

The ornamental design for a vehicle wheel lock, as shown and described.

DESCRIPTION

FIG. 1 is a perspective view showing the design;

FIG. 2 is a front elevation view of the design;

FIG. 3 is a rear elevation view of the design;

FIG. 4 is a left side elevation view of the design;

FIG. 5 is a right side elevation view of the design;

FIG. 6 is a top view of the design; and,

FIG. 7 is a bottom view of the design.

The structures depicted by way of broken lines in the drawings are shown for illustrative purposes only and form no part of the claimed design.
